UNITED STATES PATENT OFFICE

150,141

DESIGN FOR A CABINET FOR RADIO TRANSMITTER

Louis Kniep, Jr., East Orange, N. J., assignor to
Federal Telephone and Radio Corporation, New
York, N. Y., a corporation of Delaware

Application May 18, 1946, Serial No. 129,841

Term of patent 14 years

(Cl. D26—5)

To all whom it may concern:

Be it known that I, Louis Kniep, Jr., a citizen
of the United States, residing at 136A South
Munn Avenue, East Orange, Essex County, and
State of New Jersey, have invented a new, original,
and ornamental Design for a Cabinet for
Radio Transmitter, of which the following is a
specification, reference being had to the accom-
panying drawing, forming part thereof.

Fig. 1 is a front elevational view of a cabinet
for radio transmitter showing my new design;
and

Fig. 2 is a top plan view thereof.

The sides and rear of the cabinet are plain.
The characteristic features of my design reside

in the portions shown by means of full lines in
the drawing.

I claim:

The ornamental design for a cabinet for radio
transmitter, substantially as shown and de-
scribed.

LOUIS KNIEP, JR.
